F. HEDLEY AND J. S. DOYLE,
MULTIPLE UNIT DOOR CONTROL ARRANGEMENT FOR CARS.
APPLICATION FILED SEPT. 30, 1919.

1,381,638.

FRANK HEDLEY, OF YONKERS, AND JAMES S. DOYLE, OF MOUNT VERNON, NEW YORK.

MULTIPLE-UNIT DOOR-CONTROL ARRANGEMENT FOR CARS.

1,381,638.

Specification of Letters Patent. Patented June 14, 1921.

Application filed September 30, 1919. Serial No. 327,578.

To all whom it may concern:

Be it known that we, FRANK HEDLEY and JAMES S. DOYLE, both citizens of the United States, and residents, respectively, of Yonkers and Mount Vernon, county of Westchester, State of New York, have made a certain new and useful Invention in Multiple-Unit Door-Control Arrangement for Cars, of which the following is a specification.

This invention relates to multiple unit door control for cars such as are employed in street, elevated, and subway systems.

The object of the invention is to provide an arrangement for simultaneously or selectively controlling the door movements of a car, or train of cars, which is simple in structure, efficient in operation, and economical of manufacture, installation and maintenance.

A further object of the invention is to provide means which are simple for effecting selectivity of control with regard to the sides of the car on which the door control is effected.

Further objects of the invention will appear more fully hereinafter.

The invention consists substantially in the construction, combination, location, and relative arrangement of parts, all as will be more fully hereinafter set forth, as shown by the accompanying drawing, and finally pointed out in the appended claims.

Referring to the drawing:

The figure is a diagrammatic view of the system embodying our invention diagrammatically illustrating the circuitual arrangement employed in accordance therewith.

It is among the special purposes of our present invention to provide a simple arrangement for controlling the door movements on a car or train of cars from the station where the car or train of cars comes to rest to thereby eliminate the necessity of

having a conductor or other operator stationed on each car to open and close the doors thereof, and making it possible to have one operator to simultaneously effect the actuation of the doors on all of the cars where

a train is employed or to selectively effect the actuation of the doors on any one car of the train. We further propose, in accordance with our present invention, to provide means for automatically rendering operative the control system only for the doors on the side of the car from which it is de-

sired to discharge passengers or to take on passengers.

Referring to the drawing: We have shown diagrammatically the cars 1, and 60 while we have shown and will now describe a train comprising a plurality of cars of any desired number we wish it to be understood that we do not desire to be limited or restricted in this respect as the system is 65 equally well applicable to a single car system. We provide a contact rail 2 adjacent or between the tracks or located upon the track bed of the railway system, which contact rail 2 may be relatively short inasmuch 70 as the position of the car when coming to rest is always the same at the station, and one contact rail 2 is provided for each car of the train. We also provide a shoe 3 which slidably contacts with the rail 2 when 75 the car is at the station, and which shoe is in circuit connection with the switches 3^a, 4 and 5. These switches when in the position shown by dotted lines in the drawing establish circuit connection between the 80 shoe 3 and electrical devices 6, which electrical devices may be of any nature, for example, magnet valves such as are commonly employed in door operation for controlling the door movements whereby when the devices 6 are energized the doors which they 85 control are caused to assume their closed position. Such an arrangement is well known in the art whereby the devices 6 are in the nature of magnet valves and will 90 hereinafter be so termed for controlling the supply of fluid pressure and exhaust thereof from the usual well known type of pneumatic motor at present employed in door actuation on car systems of this nature. 95 The switch 4 when the position shown in full lines in the drawing establishes circuit connection from shoe 3 to wire 7 which communicates with all of the magnet valves 8, which, when energized, cause the respective doors to assume their open position. The switches 3^a, 4 and 5 are of the usual type which are thrown when the door completes its closed or its open position. In other words, when the door assumes its completely 100 open position the switches are in the position shown by dotted lines and when the doors assume their completely closed position the positions are shown by the full lines of the drawing. From the foregoing it will 110 be seen that when current is supplied to the rail 2, when the switches 3^a 4 and 5 are in

the position shown in full lines all of the magnets 8 will be energized, thereby opening all the doors on that side of the car. When the doors assume their fully opened position the switches 3^a, 4 and 5 assume their dotted line positions so that current may be supplied at will to the closing magnet valves 6 to effect the closure of all of the doors on that side of the car. The contact rail 2 is connected by means of wire 9 to a contact 10 on a switch board 11 located at the station. The contacts 10 are controlled by means of a manually operated lever 12 which is rotatably mounted and is connected to a source of current 13, one terminal of which is grounded as illustrated. A shunt or by-path circuit around switch board 11 is provided in the nature of line wire 14 which is connected to a multiple switch 15. It will be understood that we provide a contact rail 2 and a wire 9 for each car, where a train of cars is employed, and the multiple switch 15 simultaneously completes the circuit from the current source 13 to all of the lines 9 and consequently to all of the rails 2 and shoes 3 and magnet valve circuits of the system. The operation of the system thus far described is as follows: The cars in coming to rest at the station have their shoes 3 in contact with the contact rail 2. The multiple switch 15 is then closed, supplying current from the source 13, by-path wire 14, multiple switch 15, wires 9, contact rail 2 and from them on as before described to energize the opening magnets 8 of the car. When it is desired to close the doors of the car this may be effected simultaneously by again closing the multiple switch 15, as will be readily understood, inasmuch as the switches 3^a, 4 and 5 upon the doors reaching their open position have been shifted; or, if desired, the handle 12 of the selective switch board 11 may be actuated to complete the circuit connection from the current source 13 to handle 12 to any one of the contacts 10 to thereby supply current to the shoe 3 of any desired car or number of cars of the train.

50 Inasmuch as both sides of the car are equipped with doors in the usual practice of the railway art, and as it is sometimes necessary to allow passengers to board or alight from the car on either side we duplicate the equipment of the switches 3^a, 4, 5, the circuits controlled thereby and the contact shoe 3 for supplying current thereto on each side of the car. It will be apparent that by positioning the contact rail 2 at the station toward or away from either side of the car to come in contact with either of the contact shoes 3 it is possible thereby to render the system on one side of the car operative while the system on the other side of the car remains inoperative, or vice versa.

Many other modifications and changes in details will readily occur to those skilled in the art without departing from the spirit and scope of our invention as defined in the claims, and many other arrangements will suggest themselves for accomplishing the purposes of this invention, and we therefore desire to have the foregoing specification and the illustrations accompanying the same to be regarded in an illustrative sense rather than in a limiting one.

Having now set forth the objects and nature of our invention, and having shown a system embodying the principles thereof, what we claim as new and useful and desire to secure by Letters Patent is,—

1. The combination with a car and a fixed station without said car, of means carried by the car for controlling the door movements on opposite sides of said car, means located on the station for controlling said means, and means for positively determining the side of the car on which the door movements may take place.

2. The combination with a train of cars and a station outside of said train, of means carried by each of said cars for controlling the door movements on opposite sides thereof, means located in the station for controlling said means, and means for positively determining the side of the train on which the door movements may take place.

3. The combination with a car and a fixed station outside of said car, of electrical devices carried by said car for controlling the door movements on opposite sides of said car, circuits controlled from said station for controlling said devices, and means for positively determining the side of the car on which the door movements may take place.

4. The combination with a train of cars and a station outside of said train, of electrical devices carried by each of said cars for controlling the door movements on opposite sides thereof, circuits controlled from said station for controlling said devices, and means for positively determining the side of the train on which the door movements may take place.

5. The combination with a car and a station, of electrical devices carried by said car for controlling the door movements on opposite sides of said car, circuits for said devices, a shoe carried on each side of said car and controlling the circuit of the devices located on the same side therewith, a source of current, and means for connecting said source of current and the shoe of the station side of the platform.

6. The combination with a car and a station, of electrical devices carried by said car for controlling the door movements on opposite sides of said car, circuits for said devices, a shoe carried on each side of said car and controlling the circuit of the devices located on the same side therewith, a source of current, and means for connecting said source of current and the shoe of the station side of the platform.

cated on the same side therewith, a source of current, a rail located in alinement with one of said shoes and a circuit including a source of current for said rail.

5 7. The combination with a car and a station, of electrical devices carried by said car for controlling the door movements on opposite sides of said car, circuits for said devices, a shoe carried on each side of said car 10 and controlling the circuit of the devices located on the same side therewith, a source of current, a rail located in alinement with one of said shoes, a circuit including a source of current for said rail, and means for controlling said rail circuit.

15 8. The combination with a train of cars and a station, of electrical devices carried by each of said cars for controlling the door movements on opposite sides thereof, circuits on each car for said devices, a shoe carried on each side of each car and controlling the circuit of said devices thereon on opposite sides thereof, a source of current, and means for connecting the source of current 20 to one of the shoes.

25 9. The combination with a train of cars and a station, of electrical devices carried by each of said cars for controlling the door movements on opposite sides thereof, circuits on each car for said devices, a shoe carried on each side of each car and controlling the circuit of said devices thereon on opposite sides thereof, a source of current, rail sections located in alinement with one 30 of said shoes, and a circuit including a source of current for each of said rail sections.

35 10. The combination with a train of cars and a station, of electrical devices carried by each of said cars for controlling the

door movements on opposite sides thereof, 40 circuits on each car for said devices, a shoe carried on each side of each car and controlling the circuit of said devices thereon on opposite sides thereof, a source of current, rail sections located in alinement with the 45 shoes, and a circuit including a common source of current for each of said rail sections.

45 11. The combination with a train of cars and a station, of electrical devices carried by each of said cars for controlling the door movements on opposite sides thereof, circuits on each car for said devices, a shoe carried on each side of each car and controlling the circuit of said devices thereon on opposite 50 sides thereof, a source of current, rail sections located in alinement with the shoes, a circuit including a source of current for each of said rail sections, and means for controlling said rail circuits.

55 12. The combination with a train of cars and a station, of electrical devices carried by each of said cars for controlling the door movements on opposite sides thereof, circuits on each car for said devices, a shoe carried on each side of each car and controlling the circuit of said devices thereon on opposite sides thereof, a source of current, rail sections located in alinement with the 60 shoes, and a circuit including a common source of current for each of said rail sections, and means for controlling said rail circuits.

65 In testimony whereof we have hereunto set our hands on this 24th day of September, 75
A. D. 1919.

FRANK HEDLEY.
JAMES S. DOYLE.
